CLAIM

The ornamental design for a dual use bottle assembly with openable lid, as shown and described.

DESCRIPTION

FIG. 1 is a perspective view of a dual use bottle assembly with openable lid of the present invention with broken lines showing, for environmental purposes, a lip balm container received within the bottle assembly, and potential movement of a lid portion of the bottle assembly;

FIG. 2 is a side perspective view of the dual use bottle assembly with openable lid of FIG. 1 with the lip balm container removed;

FIG. 3 is a bottom perspective view of the dual use bottle assembly with openable lid;

FIG. 4 is a top perspective view thereof;

FIG. 5 is a side view thereof, the opposite side being a mirror image;

FIG. 6 is a rear view thereof;

FIG. 7 is a front view thereof;

FIG. 8 is a top view thereof; and,

FIG. 9 is a bottom view thereof.

The broken lines shown in the drawings are for environmental purposes only and form no part of the claimed design.
